UNITED STATES PATENT OFFICE.

DAVID HUESTIS, OF COLD SPRING, NEW YORK.

IMPROVEMENT IN MOLDING SHOT AND SHELLS.

Specification forming part of Letters Patent No. 28,277, dated May 15, 1860.

To all whom it may concern:

Be it known that I, DAVID HUESTIS, of Cold Spring, in the county of Putnam and State of New York, have invented certain new and useful Improvements in Molding Shot and Shell; and I do hereby declare that the following is a full, clear, and exact description of the same, reference being had to the accompanying drawings, forming a part of this specification, in which—

Figure 1 represents a vertical central section of my flasks when ready to receive the metal. Fig. 2 is a similar section of the upper one of the semi-flasks with the pattern and mold-board arranged according to my invention. Fig. 3 represents a vertical central section of the lower flask, showing the manner in which I adjust the core. Fig. 4 is an inverted plan of the gage used for adjusting the core.

Similar letters of reference in the several figures indicate corresponding parts.

This invention consists in the employment, for adjusting the pattern, of a mold-board with a central aperture to receive a circular projection on the under side of the pattern, and with a circular flange on one and a rim on the other side to fit on one side over a rim turned to the end of one of the semi-flasks, and on the other into a flange projecting from the end of the other semi-flask, said rim and flange on the semi-flasks being at the same time so arranged that they serve as guides for the flasks when the same are connected; and my invention consists, also, in combining with the flanged end of the lower semi-flask a cross-shaped gage with a half-circular recess for the purpose of adjusting the core.

To enable those skilled in the art to make and use my invention, I will proceed to describe its construction and operation with reference to the drawings.

A A' are two semi-flasks constructed of cast-iron or brass, or any other suitable material. One end of the flask A is turned in to form a rim, a, to fit into a flange, a', which projects from the end of the other flask, A'. By these means the two flasks, when brought together, will have a common center, so that a pattern one half of which has been molded in the center of the upper and the other half in the center of the lower flask will be perfect and without fault when the two flasks are brought together.

The pattern B in my molding process must be precisely one-half of the shot or shell to be produced, and it is provided with a circular projection, b, on its flat side to fit into a corresponding aperture, c, in the center of the mold-board C. This mold-board is arranged with a projecting flange, d, on one side to fit over the rim a on the semi-flask A, and its other side is turned in so as to form a rim, d', to fit into the flange a on the flask A'. When the pattern is adjusted in the mold-board on one side or on the other, and the mold-board is now placed under the semi-flask, as shown in Fig. 2, the pattern cannot help to be perfectly in the center, so that when the mold is finished the two halves in each of the semi-flasks fit together as if it were one piece, and there is no danger that one half will be on one side and the other on the other side, whereby faulty and useless castings are produced. The pattern is furnished with a pin, e, projecting from its center on the curved side of the same, and long enough to reach to the top of the semi-flasks. This pin serves to form the pouring-tube on one side, and on the other side it leaves a cavity in the sand, which receives the core-pin f, (see Fig. 3,) said core-pin being firmly attached to the core F. The lower end of the core-pin is secured in the bottom board, G, by means of a wedge, or in any other convenient manner, and the core itself is adjusted in the mold by means of a gage, H. This gage differs from the gage which is commonly used for the same purpose in two essential points. The common gage consists of a plain piece of board or sheet metal with a half-circular recess in the center, and arranged to fit into the ends of the flasks. It is obvious that by this arrangement no correct adjustment of the core can be effected, and I have therefore added another piece running crosswise with the usual gage, and giving to the whole the form of a cross with a half-circular recess in the center; and instead of guiding my gage simply by the edge of the flask I have provided the same with notches h on its edges, so as to fit in and on the flange a', giving to the same a double guide—one in an up and down and the other in a lateral direction. By these means the shot and shell can be cast with the outside perfectly smooth, and so as to form a correct globe, and with the shells the core is so adjusted that a uniform thickness of metal

throughout is effected, and the facility with which the pattern as well as the core can be adjusted is unsurpassed.

Having thus fully described my invention, what I claim as new, and desire to secure by Letters Patent, is—

1. The employment for adjusting the pattern of a mold-board, C, with a central aperture, c, flange d, and rim d', in combination with the semi-flasks A A', constructed and operating substantially in the manner and for the purpose described.

2. The combination, with the flanged end of the semi-flask A', of a cross-shaped gage, H, with notches h, constructed and operating substantially in the manner and for the purpose specified.

D. HUESTIS.
